EX

OR D 17,635

DESIGN.

—o—

H. PODMORE.

PITCHER.

No. 17,635.

Patented Aug. 16, 1887.

UNITED STATES PATENT OFFICE.

HENRY PODMORE, OF TRENTON, NEW JERSEY.

DESIGN FOR A PITCHER.

SPECIFICATION forming part of Design No. 17,635, dated August 16, 1887.

Application filed February 2, 1887. Serial No. 226,334. Term of patent 7 years.

To all whom it may concern:

Be it known that I, HENRY PODMORE, a citizen of the United States, residing at Trenton, in the county of Mercer and State of New Jersey, have invented and produced a new and original Design for Pitchers and Ewers and other Analogous Vessels, of which the following is a specification, reference being had to the accompanying photograph, forming part thereof.

10 The leading feature of my design consists in the main body of the pitcher or ewer or other analogous vessels of a rounded or bulbous form, having that part of the bulb from which the lower end of the handle springs flattened, so

15 that there shall be a circular or oval plane surrounding the base of the handle, as shown at A in the photograph. The bulb and other parts of the vessel may be elaborated and ornamented as shown in the photograph or otherwise, as the fancy may dictate.

What I claim is—

1. The design for a pitcher, ewer, or other analogous vessel having its main body of a generally rounded or bulbous form, and having one side of the bulb flattened to present a plane, 25 from which springs the lower end of the handle, substantially as shown and described.
2. The design for a pitcher, ewer, or other analogous vessel having its main body of a generally rounded or bulbous form, and having one 30 side of the bulb flattened to present a plane from which springs the lower end of the handle, the upper end thereof springing from a shoulder above said plane, as shown and described.

HENRY PODMORE.
